UNITED STATES PATENT OFFICE.

JAMES J. WALSH, OF KANSAS CITY, MISSOURI.

ADJUSTABLE WAIST PATTERN.

Application filed July 11, 1925. Serial No. 43,048.

My invention relates to improvements in adjustable waist patterns.

One of the objects of my invention is to provide a novel waist pattern, which may be easily and quickly fitted to a person or form by an unskilled person, which is simple, durable, not liable to get out of order, and which is economical to manufacture.

The novel features of my invention are hereinafter fully described and claimed.

In the accompanying drawings, which illustrate the preferred embodiment of my invention,

Fig. 1 and Fig. 2 are respectively front and side elevations of my improved waist pattern shown fitted on a form.

Fig. 3 is an enlarged sectional view on the line 3—3 of Fig. 2.

Fig. 4 is an enlarged plan view, partly broken away, of my improved pattern, the front and back portions being separated from each other, the inner side being shown.

Fig. 5 is an outside plan view of one of the slip joints with which some of the ribs are provided, the same being enlarged.

Fig. 6 is an inside view of what is shown in Fig. 5.

Fig. 7 is a sectional view on the line 7—7 of Fig. 5.

Similar reference characters designate similar parts in the different views.

The pattern comprises a front portion and a back portion adapted to be releasably fastened together when being fitted to a form, the pattern as a whole extending from the front to the rear medial parts of the form or figure.

The front portion of the pattern is provided with two extensible side ribs, one of which is intended to be disposed at the front and the other under the arm of the figure.

The front side rib has an extensible upper portion comprising members 1, 2 and 3, the member 2 being connected respectively with the members 1 and 3 by guide loops 4, and by spring clips 6, one of which is shown enlarged in Figs. 5, 6 and 7. The clips each comprising a loop 6' embracing the rib members, and a bow spring plate 5 which bears against the adjacent rib and against the loop 6', the latter being disposed in edge notches 7 provided in the plate 5 and rib members 2. T shaped extensions 6' are at the ends of the loop 6'.

The front side rib member 3 has pivoted to it the upper end of a lower rib portion comprising a member 8.

The under arm side rib comprises an extensible upper portion consisting of a member 9 and a member 10 connected by a clip 6, similar to the one already described. A lower rib portion comprises a member 11 pivoted at its upper end to the member 10.

A bust rib is fastened at its ends to the side ribs respectively, the bust rib being extensible and comprising two end members 12 and 13 respectively pivoted to the members 2 and 9. An intermediate member 14 is connected to the members 12 and 13 by clips 6.

An extensible hip rib is fastened at its ends to the lower ends of the members 8 and 11 of the side ribs, and comprises end members 15 and 16 respectively pivoted to the members 8 and 11 connected by clips 6 respectively to rib members 17 and 18. The member 17 is pivoted to a rib member 19 which is connected by a clip 6 with the member 18.

Two longitudinal ribs intermediate of the side ribs are provided. The first of the intermediate longitudinal ribs consists of a rib member 20, which is pivoted to the intermediate bust rib member 14 and is connected by a clip 6 to a rib member 21, which is pivoted to the upper end of a lower rib member 22, the lower end of which is pivoted to the members 17 and 19 of the hip rib.

The second intermediate longitudinal rib consists of a rib member 23 pivoted to the member 14 and connected by a clip 6 with a rib member 24, which is pivoted to the upper end of a lower rib member 25, the lower end of which is pivoted to the rib member 18 of the hip rib.

Two waist ribs are provided, one of which consists of a rib member 26 pivoted to the members 3 and 8 of the adjacent side rib, and which is connected by a clip 6 with a waist rib member 27, which is pivoted to the rib members 21 and 22 at their pivotal point of connection. The other waist rib comprises a rib member 28 pivoted to the members 24 and 25 at their pivotal point of connection, and slidably connected to a rib member 29 by a clip 6, the member 29 being pivoted to the rib members 10 and 11.

at the pivotal point of connection of the last named members.

An auxiliary extensible spacing rib connects the front side rib with the second intermediate longitudinal rib, and comprises a rib member 30 which is pivoted to the rib member 3 and is slidably connected with a rib member 31 by a clip 6, the rib member 31 being pivoted to the member 24 of the second intermediate longitudinal rib. The auxiliary spacing rib is disconnected from said first intermediate longitudinal rib, so that the latter may be adjusted independently of the spacing rib and the second intermediate longitudinal rib.

Neck, shoulder and scye ribs are respectively connected to each other and to the side ribs at the upper ends of the latter. The neck rib comprises a member 32 pivoted to the member 1 and slidably connected by a clip 6 with a member 33 pivoted to a member 34, which is pivoted to a member 35 slidably connected by a clip 6 with a member 36, which is pivoted to a shoulder member 37 slidably connected by a clip 6 with a shoulder rib member 38, which is pivoted to an end scye rib member 39 slidably connected to a member 40. The member 40 is pivoted to a member 41, pivoted to a member 42, which is pivoted to a member 43, which in turn is pivoted to a member 44, which is slidably connected by a clip 6 with an end scye rib member 45 pivoted to the upper end of the under arm side rib member 9.

An extensible cross rib has one member 46 pivoted to the member 2 of the front side rib, the member 46 being slidably connected by a clip 6 with a member 47 pivoted to the scye members 41 and 42 at their pivotal point of connection.

The rear portion of the waist pattern is provided with an under arm side rib, and a rear side rib, the two ribs being connected by extensible cross ribs.

The under arm side rib of the rear portion has an extensible upper portion consisting of a rib member 48 slidably connected by a clip 6 with a member 49, which is pivoted to the upper end of a lower member 50. The rear side rib of the rear portion of the pattern has an upper extensible portion comprising a member 51 slidably connected by a clip 6 with a member 52 which is connected slidably by a clip 6 with a member 53 pivoted to the upper end of a lower member 54.

An extensible cross rib adapted to aline with the bust rib of the front portion of the pattern, comprises a member 55 connected slidably by a clip 6 with a member 56, which is pivoted to the member 52.

An extensible cross rib, which alines with the bust ribs of the front portion, comprises a rib member 57 which is pivoted to the members 49 and 50 at the pivotal connec-

tion of said members, and which is slidably connected to a member 58 by a clip 6, the member 58 being pivoted to the members 53 and 54 at their point of pivotal connection.

Yielding bracing means for holding the member 54, comprises a member 59 slidably connected by a loop 4 to the member 58 and pivoted to a member 60, which is pivoted to the member 54.

An extensible cross rib, which alines with the hip rib of the front portion of the pattern, comprises a member 61 slidably connected by a clip 6 with a member 62, which is pivoted to the member 54.

A scye rib and a shoulder rib are pivotally connected with each other and with the under arm and rear side ribs respectively of the rear portion of the pattern.

Rib members 63, 64, 65, 66, 67 and 68 are pivotally connected with each other, the member 63 being pivoted to the member 48, and the member 68 being slidably connected by a clip 6 with a member 69, which is pivoted to a shoulder rib member 70, the latter being slidably connected by a clip 6 with a member 71 pivoted to a member 72, which is pivoted to a member 73 slidably connected by a clip 6 with a shoulder member 74, which is pivoted to the member 51.

An extensible cross rib comprising a member 75, pivoted to the members 67 and 68 at their point of pivotal connection, and a member 76 pivoted to the member 52 and slidably connected by a clip 6 with the member 75, connects the scye and rear side ribs of the rear portion of the pattern.

For connecting the front and rear portions of the pattern, hooks 77 are provided, one on the member 37 to engage the member 74, one on the member 38 to engage the member 70, one on the member 48 to engage the member 9, and two on the member 50 to engage the member 11.

Tapes having loops slidably engaging the front side rib of the front portion of the patterns, as designated by 78, are adapted to be releasably fastened to similar tapes 78 similarly engaging the rear side rib of the rear portion of the pattern.

The rib members which are engaged with the clips 6, are held by friction exerted by the spring plates 5 and the extensions 6' against the rib members respectively against which they bear.

When the pattern is to be fitted to a form or figure, the front and rear portions are connected together by the hooks 77, and the tapes 78 of the two portions are tied together. The longitudinal and cross ribs are adjusted to fit the form in a manner well understood. The auxiliary spacing rib comprising the members 30 and 31 permits independent adjustments of the first and second ribs and holds the latter in its adjusted position.

After the pattern has been fitted, the tapes 78 are untied and the front and rear portions are separated by unhooking the hooks 77. The pattern portions may then be used 5 in the ordinary manner in laying out the goods and properly cutting the goods.

I do not limit my invention to the structure shown and described, as many modifications, within the scope of the appended 10 claims, may be made without departing from the spirit of my invention.

What I claim is:—

1. In a dress or coat pattern, a waist pattern comprising two side ribs each having 15 an upper portion and a lower portion pivoted to said upper portion, first and second ribs intermediate of said side ribs each having an upper portion and a lower portion pivoted thereto, an extensible bust rib 20 fastened to the upper portions of said side ribs and upper portions of said intermediate ribs, an extensible hip rib fastened to the lower portions of said side ribs and to the lower portions of said intermediate ribs, two 25 extensible waist ribs respectively fastened to said side ribs and to said intermediate ribs, and an extensible auxiliary spacing rib fastened to the upper portion of one of said side ribs, and fastened to the upper portion

of the second intermediate rib and adjustable 30 independently of said first rib.

2. In a dress or coat pattern, a waist pattern comprising two side ribs each having an upper extensible portion and a lower portion pivoted thereto, first and second intermediate ribs each having an extensible upper portion and a lower portion pivoted thereto, an extensible bust rib pivoted to the upper portions of said side ribs and to the upper portions of said intermediate ribs, an extensible 40 hip rib pivoted to the lower portions of said side and intermediate ribs, two extensible waist ribs respectively pivoted to said side ribs and said intermediate ribs, and an extensible auxiliary spacing rib pivoted 45 to one of said side ribs and to the second intermediate rib and adjustable independently of said first rib.

3. In a pattern of the kind described, a cross rib, a longitudinal rib member pivoted thereto, a loop carried by the cross rib, a member longitudinally slidale in said loop, and a bracing member pivoted to the last named member and said longitudinal rib member. 50

In testimony whereof I have signed my name to this specification.

JAMES J. WALSH.
